RAILWAY SLEEPING CAR

David A. Crawford, Chicago, Ill., assignor to The
Pullman Company, Chicago, Ill., a corporation
of Illinois

Application January 25, 1943, Serial No. 473,451

40 Claims. (Cl. 105—316)

1

This invention relates to railway sleeping cars of the type utilizing open sections having upper and lower berths for the accommodation of passengers at night and which are made up for use of the sections as seating areas during the day at which time the bedding and the curtains used for enclosing the sections at night are stored in the respective upper berths.

The primary purpose of the invention is to improve the open section accommodation in a manner to increase its acceptability to the traveling public.

An important object of the invention is the provision of a more comfortable lower berth in the form of a full length bed which is adapted to be made ready for occupancy more easily and which is foldable into a wall clear of the section for daytime use of the space.

A further object of the invention is to provide an upper berth arrangement of improved design which affords greater spaciousness in the section when the berth is closed and which is adapted to be folded into a position overhead when not in use.

Another object of the invention involves an arrangement of open sections disposed in pairs throughout the length of a car without dividing partitions between the respective sections of the pairs and having a fixed partition separating each pair and wherein disappearing beds are accommodated in the fixed partitions with partitions normally folded therein adapted to separate the respective sections of each pair when the beds are opened for use.

A still further object of the invention includes open sections disposed in pairs with fixed dividing partitions therebetween and without intervening partitions between the respective sections of each pair wherein individual, adjustable and reversible seats which may be collapsed to accommodate a bed in each section are arranged in a manner whereby the seating capacity of the respective sections in each pair may be varied.

Another and important object of the invention is the provision of a combination of full length upper and lower beds adapted both to be folded completely out of the space normally used in daytime and wherein one bed is foldable endwise in a direction at right angles to the folding movement of the other bed which is doubly hinged to fold jackknife fashion out of the path of movement of the first bed.

An important feature of the invention contemplates upper and lower fold-away beds adapted to be extended and retracted at right angles

2

one to the other wherein each bed is of full length and are both accommodated within the length and width of one bed.

The foregoing and other objects of the invention are attained by the arrangement herein-after to be described and as shown in the accompanying drawings in which—

Fig. 1 is a plan view of a portion of a railway car equipped with the open section arrangement of this invention showing the sections disposed in pairs between fixed partitions with those upon one side of the central aisle made up for night use and those on the other side of the aisle set up for day use with the individual seats reversed for use respectively in each section;

Fig. 2 is a cross sectional view through the car taken on the line 2—2 of Fig. 5 illustrating the sections upon opposite sides of the aisle, both made ready for daytime use and showing the adjustable and reversible dividing seats on one side and the full width folding seat which operates with the bed on the other side;

Fig. 3 is a similar cross sectional view taken on the line 3—3 of Fig. 1 but showing the sections made up for night occupancy with the berths and curtain arrangement clearly illustrated on one side and the folding partition dividing adjoining sections shown in position on the other;

Fig. 4 is a fragmentary detail sectional view taken on the line 4—4 of Fig. 3 illustrating a manner of supporting the dividing partitions when the berths are made up;

Fig. 5 is a longitudinal sectional view through the aisle of the car taken on the line 5—5 of Fig. 2 showing a pair of adjoining sections as made up for daytime use;

Fig. 6 is a similar view showing the adjoining sections made ready for night occupancy with the curtains shown in place on one section and the other broken away in part to show the relation between the folding bed and seats and the upper berth with the dividing partitions illustrated in operative position;

Fig. 7 is a detail perspective view of the reversible folding seat shown in disassembled relation to its supporting base;

Fig. 8 is a detail sectional view through the seat and base indicating the backrest in normal position in full lines and shown in reclining and folded positions respectively by broken lines;

Fig. 9 is an elevational view of the seat end arrangement illustrating the folding armrest and adjusting mechanism for the seat back with parts broken away better to reveal the mechanism; and

Fig. 10 is a sectional view taken on the line

10—10 of Fig. 9 through the seat end and showing the adjusting mechanism and armrest.

In the drawings 10 represents a railway car having side walls 11 and 12, in which windows 13 are disposed, and having a roof construction 14 and an underframe providing a floor 15. The car is provided with a central longitudinal aisle 16 upon opposite sides of which the open sections of this invention are disposed. Transversely disposed fixed partitions 17 extending from the respective side walls to the aisle are located at intervals throughout the length of the car such as to divide the open sections into pairs 18—19 at each side of the aisle. The sections of each pair are separated by similar reversible seats 20 and 21 which are disposed side by side to face normally in opposite directions whereby to provide an individual seat for each section. Each of the open sections is adapted to be converted for night occupancy with upper and lower berths and to this end each of the fixed partitions 17 is equipped with a pair of folding beds 25 opening in opposite directions into adjoining pairs of sections so that each pair of sections, when made ready for night occupancy, has a bed from each of the adjoining fixed partitions.

The fixed partitions 17, as best shown in Figs. 1 and 5, are of substantial depth longitudinally of the car and such as to accommodate two of the folding beds 25. For this purpose the partitions each have an extended aisle wall portion 26 and a dividing wall 27 separating the sections upon opposite sides of the partitions. The aisle portion 26 is of such extent as to provide a receptacle 28 at each side of the wall 27 of sufficient depth to accommodate the respective folding beds 25 for the adjoining sections which are adapted to fold endwise into the respective receptacles. These folding beds comprise the lower berths in the sections of each pair and are operable individually as the various sections in the car are made up for night use. Each of the folding beds 25 consists of a bunk 30 having side and end rails 31 and 32 respectively and a bottom connecting portion 33 for supporting a mattress and bedding 34. As best shown in Figs. 2, 3 and 6, the bottom 33 of the bunk has its entire central area, comprising the major portion thereof, composed of a flexible panel 35 which provides a resilient support for the mattress 34, thus enabling a mattress of less depth to be utilized with the same degree of comfort as a thicker mattress might give without the flexible base. The exposed side of the flexible base 35 is such as to present a pleasing appearance in the section from which it can be viewed.

A panel 36 of substantially the width of the bunk is hingedly mounted on the end rail 32 of each bunk at that end of the bunk which is disposed at the central position between the fixed partitions 17 when the bed is horizontal and is of such height as to extend upwardly to the ceiling and thus serves to separate each section of the various pairs of sections throughout the car for individual night occupancy and rendering every section entirely independent of any other section in the car whereby each section may be made up without disturbing any other. The vertical operative position of the panel 36 is maintained by means of an interlocking connection 37 with the intermediate depending partition 38, as best shown in Figs. 4 and 6, and when the bed is to be folded away for day use of the section the panel is adapted to be folded flat upon the mattress 34 by means of the hinge 39 for accommodation with

the bed within the receptacle 28 as shown in Fig. 5. The panel 36 has an auxiliary section 40 at the edge adjacent side wall 11 or 12, as the case may be, hingedly mounted with respect thereto by means of hinge 41 and which, when the panel is vertical for separating adjoining sections, is adapted to close the space between the panel and the adjacent side wall, as shown in Figs. 1 and 3. Torsional springs 42 maintain the section 40 in extended position while the panel 36 is in operative position but when the panel is disposed in its inoperative position the section is adapted to be folded back upon the panel by means of the hinge 41 where it is maintained in such retracted condition by means of bracket 43 for entry into the receptacle 28 with the bed when the bed is folded to its closed position. It will be noted, when both lower berths between any pair of fixed partitions 17 are made up for night use, that the adjoining sections are separated by the two panels 36 of the respective berths and which are attached upon opposite sides of the intermediate depending or drop partition 38 wherefore either of the sections may be made ready for day use without the necessity of also setting up the other, all as best shown in Fig. 6.

The beds 25, as before stated, are foldable endwise from a horizontal position for use to a vertical closed position into the receptacles 28 in the relatively deep fixed partitions 17 and the beds being of rigid full length construction intended for use in association with upper berths, necessitates mechanism for pivotally mounting the beds which will cause each bed to close to its vertical condition in a position sufficiently low to accommodate an upper berth in the space above the upper end thereof and which causes the bed to open to its horizontal position for use at the proper or normal height above the car floor and above the folded section seats while functioning substantially within its own length. The pivotal mounting means for each bed comprises a fulcrum bar 45 extending across the full width of the bed and mounted at its opposite ends in bearings 51 in the side wall 11, or 12, and seat end 50 at the aisle position respectively and about which the bed pivots during opening and closing movements. In order to accommodate the full movement of the bed in the space provided while opening the bed to the proper height the fulcrum bar 45 is mounted forwardly of the face of the bed, as best indicated in Fig. 5, and spaced arms 52, rigid with the bar 45, are disposed respectively at each side of the bed and connect the fulcrum to the bed at a point substantially removed from the location of the fulcrum bar and disposed thereabove when the bed is vertical. The arms 52 are pivotally associated with the bed through connections 53 so that actually the bed moves about the two pivot points 45 and 53 during both opening and closing movements and might be said to be mounted in a fulcrum yoke formed by the bar 45 and rigid arms 52. Due to the use of the two point pivotal action in the operation of the bed it is necessary to control the movements thereof through the proper orbit and for this purpose tracks 55 are provided, one at each side of the bed and which are adapted to cooperate with trunnions 54 on the bed to regulate the initial opening movements and final closing movements thereof. The tracks 55 comprise brackets which are secured to the floor of the car at 56 and extend upwardly therefrom above the level of the lower end of the bed in its ver-

tical position, where they incline downwardly at 57 toward the rear of receptacle 28 to provide slots 58 for the reception of trunnions 54 and thereby support the bed in its closed position. The rear wall of the slot 58 in each bracket is formed by upwardly curving portion 59 from whence the brackets extend horizontally rearward to be connected to the dividing wall 27 as at 60. The bed 25 is counterbalanced for ease of operation during the opening and closing movements by means of tension springs 61 which, as shown, are secured to the bed at the lower end in batteries of two at each side, as at 62, and to the car floor through the medium of an angle member 63. In the operation of the bed from vertical closed position as shown in Fig. 5 to fully extended horizontal position as shown in Fig. 6, the operator grasps the operating bar 65 provided for that purpose and extending across the flexible base portion 35 of the bed for attachment to the rigid bottom portions at opposite sides thereof as at 64 and as best illustrated in Fig. 2. Pulling the bed outwardly by means of the operating bar causes the fulcrum yoke to pivot about the bar 45, with the bed moving relatively and lifting the trunnions 54 in the slots 58 until the surface of the bed rests against the bar 45 whereupon the bed and fulcrum yoke move as a unit about the pivot 45 with the trunnions 54 passing the curved portions 59 of the respective tracks 55 as the bed is lowered to horizontal position against the counterbalancing resistance of springs 61 which maintain the relationship of the trunnions 54 with the slots 58 during the initial operation and urge the bed towards the bar 45 as the tracks guide the operation. The hinged end of the bed finds support upon the fulcrum bar 45 when the bed is in horizontal open position.

It will be seen that before lowering the bed 25 for use, it is first necessary to fold the individual seats 20 and 21 and to lower the hinged backrest 66 of the full width section seat 67 which is disposed along side of the window 13 with the backrest reclining against the face of the bed and hinged at 68 to fold flat against the seat when the bed is to be opened. The seat extends from the side wall 11 or 12 to the seat end 50 and the seat back is adapted to conceal the fulcrum mechanism when the bed is closed and the seat back disposed for use of the seat. When the bed is lowered to horizontal position, the panel 36 may be raised to vertical position and attached to the drop partition 38 by means of the connection 37 for separation of the adjoining section and to support the free end of the bed after which the panel section 40 may be extended to close the gap between the side wall and the panel 36. When it is desired to close the bed the separating panel 36 and its auxiliary 40 are folded flat upon the mattress 34 and the bed then may be raised very easily with the assistance offered by the counter-balancing springs 61 which are adjusted to exert sufficient tension at all times materially to assist in the closing operation. As the free end of the bed is lifted the operations with respect to the pivotal action are in reverse sequence to those of the opening operations. The bed rotates about the pivot 45 as a unit with the fulcrum yoke until the trunnions 54 come in contact with the sloping surfaces 57 on the tracks 55 where engagement is maintained by the springs 61 and after which the bed moves relatively to the fulcrum yoke away from its contact with the bar 45 as the trunnions slide along

the incline 56 into the slots 58 where the bed rests in fully closed position. With the bed fully closed it will be seen that the connection 53 of the fulcrum yoke to the bed is disposed beyond dead center 45 so that the arms 52 act as struts to prevent accidental displacement of the bed from its fully closed condition and renders it necessary positively to actuate the bed by means of the operating bar 65 before it can be withdrawn from the receptacle 28.

When the respective pairs of adjoining sections are made up for day occupancy the respective sections of each pair are joined without any intervening partition, but the individual seats 15 20 and 21 separate the sections for independent use. The independent seats are adjustably and pivotally mounted upon a central platform or pedestal 70, as best shown in Figs. 7 and 8. This seat support is a permanent fixture and is open underneath for the accommodation of luggage. The platform of the seat support is provided with aligned laterally extending slots 75 which are adapted to receive the respective pivots 77 for the seats 20 and 21 to provide for their adjustment laterally. The seats 20 and 21 each have a base 78, through the extended rear portion of which, the respective pivots 77 are adapted to extend as at 79 and be secured by means of washers 81 and stud bolts 82. By the single pivotal connection of each seat with the support 70 it will be seen that the individual seats may be rotated completely to face either both in the same direction in either section or in opposite directions with one seat available to each section. 35 The seat cushion 83 is constructed directly upon the base member 78 and the backrest 84 is supported from the base by mechanism adapted to provide for folding of the backrest to permit of lowering the bed 25 and also for adjustment thereof to a plurality of reclining positions as indicated in Fig. 8.

The arrangement for the twofold operation of the backrest includes multiple hinged brackets adapted to provide for hinging of the backrest both forwardly and rearwardly whereby it may be folded or adjusted for reclining respectively. A fixed bracket 85 is disposed at each side of the seat cushion 83 adjacent the rear portion thereof and rigidly secured to the base member 78. This bracket extends upwardly at the inner side of seat end 86 and is provided at its upper extremity with a pivot opening 87 and a limit stop 88 radially disposed with respect to the pivot point. Disposed between the fixed bracket 85 and the backrest 84 and pivotally connected to each is the adjusting bracket 90 which provides for the double action of the backrest. The bracket 90 is pivotally associated with the pivot 87 where the connection is made by means of a headed pin 91 secured through the pivot opening 87 to the bracket 85. A radially disposed stop 89 on bracket 90 directly opposes stop 88 on the bracket 85 and, as best indicated in Fig. 10, it will be seen that the respective stops are offset laterally one inwardly and the other outwardly to bring their engaging surfaces into alignment and thereby upon contact to limit the forward pivotal movement of the bracket as shown in Fig. 9. This position of the bracket represents the normal sitting position of the backrest and is maintained by means of an adjusting device 95 which may be released to change the position of the backrest at will. The brackets 90 at opposite sides of the seat are rigidly secured together for simultaneous movement by

means of a connecting bar 99 thereby to insure equal movement of the backrest at both sides and provide even resistance to load across the full width of the seat. The adjusting device is mounted within the seat end structure 86 and is in the form of an L-shaped member having its shorter arm arranged upright adjacent to the bracket 90 and its longer arm disposed horizontally with a pivotal mounting at the point of juncture of the horizontal and upright arms. The pivotal mounting for the locking device comprises a headed pin 94 secured to the relatively heavy inner wall 93 of the seat end member 86 and upon which the member 95 fulcrums to move the upright 92 relatively to the bracket 90 by manipulation of the horizontal arm 96. The upright 92 is offset at 97 to bring its operative portion in a plane besides the bracket 90 where it is in position to engage with projection 98 to lock the backrest either in sitting position or in one or more reclining positions.

The various positions of the backrest are determined by a series of notches 100 in the forward edge of the upright 92 which are adapted selectively and releasably to interlock with the projection 98 in a manner whereby the upright acts as a strut between the projection and the connection 94 to the seat end and thereby support the backrest in any selected position. The number of notches provided determines the number of positions in which the backrest may be supported. Coil springs 101 are disposed in tension between the brackets 90 at opposite sides of the seat and an anchor 103 on the respective seat ends and function to return the backrest toward normal position as the adjusting device 95 is released and prevent any sudden falling away of the backrest when it is desired to move it to a reclining position, which is done against the resistance of the springs. The spring is covered with upholstery fabric 102 to protect the hands or person of anyone using the seat and coming in contact therewith, and is attached to bracket 90 through the medium of a projection 104 which is laterally offset to bring the spring as closely adjacent the inner side of the seat end as possible. The horizontal arm 96 of the adjusting device has an operating portion 105 extended through the outside plate 106 of the seat end 86 which is operable substantially vertically in the radial slot 107 to manipulate the upright 92 with respect to the locking member 98 on the bracket 90 whereby the backrest may be adjusted by a user from a sitting position without the necessity of arising from the seat. A leaf spring 108 secured in the seat end 86 between walls 93 and 106 as at 109 exerts a downward pressure at all times on the horizontal arm 96 to maintain the interlocking engagement between the projection 98 and notches 100 except when released by manipulation of the operating handle 105. The backrest 84 is disposed between the brackets 90 at the opposite sides thereof and is pivotally connected with the brackets as at 110 for hinged folding movement forwardly and a stop 111 at each side of the backrest and engageable with stops 112 on the respective brackets limits backward movement of the seatback relative to the brackets and determines the normal position thereof. This single hinged action of the backrest is entirely independent of the movement thereof about the pivot 91, being in the opposite direction thereto, and is solely for the purpose of collapsing the

seat when the folding bed 25 is to be lowered to a horizontal position thereover.

As best shown in Figs. 9 and 10, the individual seats 20 and 21 are each provided with armrests 120 which are adapted to be folded out of the way in order to accommodate the folding bed 25 in its horizontal position. Each armrest comprises an inverted U-shaped member 121 of open construction mounted in pivotal relation to the seat end structures 86 and having its uppermost surface provided with an upholstered pad portion 122. The member 121 is in the form of a bail straddling the respective seat end structures where it is pivotally connected by means of headed pivot bolts 123 by means of which it is adapted to be folded to a depending position against the outer face of the seat end, as best shown in Figs. 2 and 6. It is only necessary to lower the armrests when it is desired to make up the bed 25 at which time it will be seen that the armrests may be disposed entirely out of the way. When the armrests are disposed in their normally upright position, indicated in Figs. 9 and 10, the upholstered pad member 122 prevents the hinged movement of the backrest 84 about the pivot 110, therefore, before the backrest can be folded to accommodate bed 25 it is first necessary to lower the armrests. The vertical upright position of each armrest is determined by means of a stop member 124 extending into the path of movement of a vertical leg of the member 121 from a vertically extended portion 125 on the seat end structure 86 and contact with which limits the upward movement of the armrest. When the armrest is disposed in contact with the stop 124, a spring pressed bolt 126 mounted in the vertical extension 125 is adapted to be entered into an opening 127 in the member 121 to lock the armrest in normal position. Spring 128 urges the bolt 126 home and an operating knob 130 provides a convenient means of retracting the bolt when it is desired to lower the armrest. To lower the armrest on the wall adjacent side of the seat at that position it is first necessary to rotate the seat about the pivotal mounting 11 an amount sufficient to enable the armrest to clear the side wall as it is lowered, after which the seat may be returned to normal position until it is desired to restore the armrest.

It will be noted, as best shown in Figs. 1, 2 and 5, that a removable screen is provided between adjoining seats 20 and 21 in the form of a flexible and elastic shield 132 releasably secured to the backs of the respective seats by means of grommets 133 whereby an increased degree of privacy is afforded the occupant of each seat when the respective seats are facing in opposite directions into the adjoining sections.

Each section space is provided with an upper berth 135 which, when the upper and lower beds are made up, is disposed in the same vertical plane with the lower and coextensive therewith and is comprised of a doubly hinged bed adapted to fold completely out of the path of movement of the endwise foldable bed 25. As best shown in Figs. 2 and 5, the bed 135, when folded, occupies a position adjacent the upper portion of the section space and immediately above the swinging end of bed 25 in its uppermost position so that the latter bed may be operated without any interference whatever from the upper bed. The bed 135 in each section extends continuously between and is hingedly mounted from the intermediate partition 38 on one side and the di-

viding wall 27 on the other and is composed of a first hinged member 136 pivotally connected at 137 with the partition 38 and at 138 with the dividing wall 27 and a second member 140 pivotally mounted at opposite ends as at 139 within the first member at that side thereof distant from the pivotal supporting connections 137 and 138 and adapted to be folded into the latter member and the two members then folded to their retracted position above the path of the arc described by the bed 25 during its opening and closing movements. The first hinged member 136 is constructed in the form of a pan having side and end walls 141 and 142 respectively and a bottom wall 143 whereby to receive and fully enclose the member 140. As before stated, the member 136 is pivotally mounted between the partitions 38 and 27, the pivots 137 and 138 being located at that side of the pan adjacent the side wall 10 or 11 as the case may be and the pivotal connections with the pan being made through the respective end walls 142 at the side of the pan remote from the particular side wall of the car. Torsional spring counterbalancing mechanisms 145 disposed one at each end of the bed are connected with the pan through the medium of flexible chains 144 also secured to the respective end walls 142 and function to reduce the effort required to operate the bed both in the opening and closing movements. In the opening movement, the counterbalancing mechanisms relieve the operator of a substantial part of the weight of the entire bed including the members 136 and 140 until they reach the fully opened position of the pan 136 with that member depending vertically from its pivots 137 and 138 adjacent the sidewall of the car where it is secured against movement by means of an automatically operating spring pressed catch 146, after which the member 140 may be readily swung to a horizontal position, all as best shown in Fig. 3. During the closing movement, the counterbalancing mechanisms 145 materially assist in raising both the members 136 and 140, after the member 140 has been folded into the pan 136, to their normally retracted horizontal position in the upper regions of the section space where they are supported by means of a latch 149 on the partition 38 releasably engaging the panel 136 and a retractable supporting member 150 on the wall 27 and engageable beneath the bottom 143 of the member 136. The counterbalancing devices 145 comprise torsional spring mechanisms of a well known type each including a spring functioning in torsion and mounted in the pulley 147 to which the chain 144 is attached and the whole assembly mounted respectively upon the depending partition 38 and the dividing wall 27 by means of a spider frame 148, in a position above the retracted bed 135 where most effective counterbalancing of the weight of the bed may be accomplished.

The member 140 of the bed 135 comprises a bed frame of rectangular formation having side and end rail members 151 and 152 respectively joined in a manner leaving the space between these rails entirely open and this opening is closed by a flexible base 155 secured at each of its four edges to the side and end rails whereby to provide resilient support for mattress and bedding 154 carried in the member to form the sleeping surface. With the bed frame 140 pivoted at 139 in the pan 136 its side adjacent the side wall of the car will be supported by the

pan, but the free swinging side of the frame adjacent the aisle is supported by flexible chains 153 connected to the end rails 152 at each end of the bed and anchored to the drop partition 38 and wall 27 above the uppermost position of the bed so that the chains are concealed within the pan when the bed is retracted. A releasable latch 156 at each end of the bed holds the frame 140 within the pan 136 during the operating movements of the pan and must be released before the bed frame can be lowered from the pan. Headlining 157 finishes off the interior of the upper berth space to provide a pleasing appearance to the occupant of this accommodation. Assuming that the bed 135 is disposed in its fully retracted position indicated in Figs. 2 and 5 and it is desired to make up the bed for use, after the lower berth has been made up, it is first necessary to retract the member 150 which supports the end of the bed adjacent the dividing wall 27 when the bed is closed and then release the latch 149 whereupon the pan 136, with the bed 140 contained therein, may be swung downwardly about the supporting pivots 137 and 138, with the counterbalancing mechanisms 145 relieving the operator of the combined weight of the pan and bed, until the pan reaches its final position depending vertically adjacent the side wall where the latch 146 engages and retains the pan against the tension exerted by the counterbalancing mechanisms. With the pan 136 secured in its fully open position, the bed 140 may then be opened by releasing the latches 156 so that the bed may be swung about the pivots 139 in the pan to a horizontal position, where it is supported by the chains 153 for use. Closing of the bed is accomplished in reverse sequence with the bed 140 first being folded into the pan 136 and secured by latches 156 whereupon the latch 146 may be released and the pan, with the bed therein, then swung to its normally retracted horizontal position above the section space with the counterbalancing assistance of the mechanism 145, where the latch 149 will be engaged automatically to support the one end of the bed while the latch 150 is being extended to support the other end after which the lower bed 25 then may be folded into the receptacle 28. Since the upper berth 135 extends continuously between partition 38 and dividing wall 27 and is operatively disposed in the same vertical plane with lower bed 25, it will be seen that one end of the upper bed extends within the receptacle 28 containing the lower bed 25 so that the lower bed must be extended before the upper bed can be lowered to operative position and conversely the upper bed must be disposed in its fully retracted position before the lower bed can be closed into the receptacle. This interdependent relation in the operations of the beds provides an arrangement wherein upper and lower fold-away beds each of full length may be accommodated within the space of a single bed length.

Both beds of each section, when made up for occupancy, are enclosed by curtains individual to each berth. Curtains 158 for the upper berth and separable at the center for entry into the berth are suspended from supporting rod 159 while curtains 160 for the lower berth, also separable at the center for entry into the berth, are suspended from rod 161 on the upper berth outer side rail 151. The curtains for both berths in each section are secured at one side to the aisle wall 26 through the medium of any suitable fas-

11

tenting means 162 and at the other side to the respective hinged panel 36 by means of suitable fastenings 163.

A central over head duct 165 for conditioned air is located over the aisle ceiling 166 and is adapted to supply fresh air to the individual upper and lower berth spaces of the respective sections at opposite sides of the aisle by means of vertical branch ducts 167 connected with the main duct as at 168 and from which the air issues to the respective upper and lower berths by means of individually controlled outlets 169 and 170 located inwardly of the curtain position so that each occupant is supplied at all times with sufficient fresh air even though the sections are 15 made up for night use.

In the normal use of the arrangement herein disclosed, the individual seats 20 and 21 which serve to divide the adjoining sections are provided for use by the occupants holding the upper berth reservations and the full width seats 67 are utilized for occupancy by passengers holding lower berth reservations and the space beneath the seat support 70 for the individual seats and that beneath the full width seat 67 is used by the occupants of the upper and lower respectively for the accommodation of their luggage.

From the foregoing, it will be seen that a railway sleeping car has been provided in which open section accommodations have been disposed at opposite sides of a central aisle and arranged in pairs between fixed partitions without benefit of dividing partitions between adjoining sections of each pair and wherein pairs of individual and reversible seats are utilized to separate such adjoining sections in a manner whereby the sections may be changed at will to accommodate two and four seated passengers respectively or three passengers in each and in which sleeping accommodations are provided in the form of full length fold-away beds operable in directions at right angles to each other but occupying the same vertical plane when in use and both functioning within the space limitations defined by the width and length of one bed. By the combination of features disclosed applicant obtains a more spacious interior with more desirable accommodations and provides more comfortable upper and lower beds of a design and arrangement which utilizes the available space to the greatest efficiency and affords the most convenience and comfort to the occupants and at the same time permits of both beds being made up prior to the time of their actual use whereby in operation it is necessary only to open the beds and hang the curtains.

What is claimed is:

1. A vehicle having a space of substantially the length of a bed, upper and lower beds in said space operatively disposed in parallel overlying relationship substantially in vertical alignment and foldable in directions at right angles to positions in horizontal and vertical planes respectively, said upper bed being foldable about an axis extending longitudinally thereof and said lower bed being foldable about an axis extending laterally thereof.

2. A vehicle having a space of substantially the length of a bed, upper and lower beds in said space disposed in parallel overlying relationship substantially in vertical alignment when in operative position and foldable through intersecting planes in directions at right angles to positions disposed horizontally and vertically respectively, one of said beds being foldable about an axis ex-

70

12

tending longitudinally thereof and the other bed being foldable about an axis extending laterally thereof.

3. A vehicle having a space of substantially the length of a bed, a plurality of folding beds in said space disposed in parallel overlying relationship substantially in vertical alignment when in operative position and foldable in directions at right angles to inoperative positions disposed horizontally and vertically respectively, one of said beds being foldable about an axis extending longitudinally thereof to said horizontal position and the other bed being foldable about an axis extending laterally thereof to said vertical position.

4. A vehicle having a space of substantially the length of a bed, a lower bed in said space foldable from a horizontal operative position to a substantially vertical inoperative position at 20 one end of the space and an upper bed foldable in a direction at right angles to the direction of folding of the lower bed from a horizontal operative position on a plane in parallel overlying relationship and substantially vertical alignment 25 with said lower bed when the lower bed is in operative position to an inverted horizontal inoperative position on a plane disposed in overlying relationship to the operative plane of the upper bed and substantially in vertical alignment with the operative positions of the upper and lower beds.

5. A vehicle including a side wall and a longitudinal aisle and having a space of substantially the length of a bed disposed between said wall and the aisle, a lower bed in said space foldable in a single motion from a horizontal operative position to a vertical inoperative position, and an upper bed foldable from a horizontal operative position to an intermediate substantially vertical position and thence to a horizontal inoperative position.

6. A vehicle including a side wall and a longitudinal aisle and having a space of substantially the length of a bed disposed between said wall and the aisle, a lower bed foldable directly from a horizontal operative position in said space to a substantially vertical inoperative position at one end of the space, and an upper bed foldable from a horizontal operative position in parallel overlying relationship and substantially vertical alignment with the operative position of the lower bed to an intermediate substantially vertical position at one side of said space and thence to a horizontal inoperative position above the level of the vertical inoperative position of the lower bed.

7. A vehicle having a space of substantially the length of a bed, upper and lower beds in said space operatively disposed in parallel overlying relationship substantially in vertical alignment and foldable in directions at right angles to inoperative positions in horizontal and vertical planes respectively and means pivotally supporting said upper bed including a pan member hingedly mounted and movable from a horizontal position in an upper portion of said space to a vertical position at one side of the space, said upper bed being movable with said pan from said horizontal position to said vertical position and pivotally mounted in the pan for movement relative thereto from the vertical position to horizontal operative position.

8. In a vehicle having spaced partitions, a folding bed vertically disposed in inoperative position in each side of each of said partitions and

13

movable to oppositely extending horizontal operative positions at respectively opposite sides of the partitions, said beds when in operative positions jointly extending from one partition to the other substantially in end abutting relation, and means providing a separating wall between the beds at said abutting ends.

9. In a vehicle having a space of substantially the length of two beds, a partition dividing said space, a pair of folding beds vertically disposed in inoperative positions at respectively opposite sides of said partition, said beds being movable respectively to oppositely extending horizontal operative positions at the respective sides of the partition defining the length of said space, and a foldable bed operatively disposed in parallel overlying relation to each of said first-named beds in their operative positions, said last-named beds being movable in directions at right angles to the folding movements of the respective first-named beds to horizontal inoperative positions above the level of the normal operative positions of all of the beds.

10. In a vehicle having oppositely disposed spaced partitions, a pair of beds between said partitions including a folding bed vertically disposed in inoperative position in each of the partitions and movable to horizontal operative positions jointly extending between the partitions substantially in end abutting relation, means for mounting the beds in pivotal relation to the respective partitions, and a second pair of beds between said partitions comprising an individually foldable bed operatively disposed in parallel overlying relationship and in substantially vertical alignment with each of the first-named beds in their operative positions, said last-named beds being movable in directions at right angles to the folding movements of the respective first-named beds to horizontal inoperative positions above the normal operative positions of all of the beds.

11. In a vehicle having oppositely disposed spaced partitions, a pair of beds between said partitions including a folding bed vertically disposed in inoperative position in each of the partitions and movable to horizontal operative positions jointly extending between the partitions substantially in end abutting relation, and means providing a separating wall between the beds at said abutting ends.

12. In a vehicle having a side wall and spaced partitions disposed normal to the side wall, a pair of beds between said partitions including a folding bed vertically disposed in inoperative position in each of the partitions and movable to horizontal operative positions jointly extending between the partitions substantially in end abutting relation, means for mounting the beds in pivotal relation to the respective partitions, a second pair of beds between said partitions comprising an individually foldable bed operatively disposed in parallel overlying relationship and in substantially vertical alignment with each of the first-named beds in their operative positions, and means pivotally supporting each of said second beds including a pan member hingedly mounted and movable from a horizontal position at a level higher than said vertically disposed first-named beds to a vertical position adjacent said side wall, said second beds being movable with said pans from said horizontal positions to said vertical positions and pivotally mounted in the pans for movement relative thereto from the vertical positions to horizontal operative positions.

14

13. In a vehicle having oppositely disposed spaced dividing partitions, a pair of beds between said partitions including a folding bed vertically disposed in inoperative position in each of the partitions and movable to horizontal operative positions jointly extending between the partitions substantially in end abutting relation, a folding partition member mounted on at least one of said beds and foldable into the bed when the bed is inoperatively disposed and movable to a vertical operative position when the bed is horizontal to separate the space between said dividing partitions into individual compartments for the respective beds, and a second pair of beds between said dividing partitions comprising an individually foldable bed operatively disposed in parallel overlying relationship and in substantially vertical alignment with each of the first-named beds in their operative positions, said second beds being movable in directions at right angles to the folding movements of the respective first-named beds to inoperative positions out of the operative paths of the first-named beds.

14. In a vehicle having oppositely disposed spaced dividing partitions, a pair of beds between said partitions including a folding bed vertically disposed in inoperative position in each of the partitions and movable to horizontal operative positions jointly extending between the partitions substantially in end abutting relation, and a folding partition member mounted on at least one of said beds and foldable into the bed when the bed is inoperatively disposed and movable to a vertical operative position when the bed is horizontal to separate the space between said dividing partitions into individual compartments for the respective beds.

15. In a vehicle having a partition, a folding bed in the partition disposed vertically in inoperative position and movable to a horizontal operative position extending outwardly of the partition, and a folding partition member mounted on the bed and foldable into the bed when the bed is inoperatively disposed and movable to a vertical operative position in spaced relation to said first-named partition when the bed is horizontal to provide a compartment in said vehicle individual to said bed.

16. In a vehicle having a partition, a folding bed in the partition disposed vertically in inoperative position and movable to a horizontal operative position extending outwardly of the partition, a folding partition member mounted on the bed and foldable into the bed when the bed is inoperatively disposed and movable to a vertical operative position in spaced relation to said first-named partition when the bed is horizontal to provide a compartment in said vehicle individual to said bed, and a second bed between said partitions operatively disposed in parallel overlying relationship and in substantially vertical alignment with the first-named bed, said second bed being foldable in a direction at right angles to the folding movement of the first-named bed to an inoperative position out of the operative path of the first-named bed.

17. In a vehicle having a partition, a folding bed in the partition disposed vertically in inoperative position and movable to a horizontal operative position extending outwardly of the partition, a folding partition member mounted on the bed and foldable into the bed when the bed is inoperatively disposed and movable to a vertical operative position in spaced relation to said first-named partition when the bed is hori-

zontal to provide a compartment in said vehicle individual to said bed, a second bed between said partitions operatively disposed in parallel overlying relationship and in substantially vertical alignment with the first-named bed, and means pivotally supporting said second bed including a pan member hingedly mounted and movable from a horizontal position at a level higher than said vertically disposed first-named bed to a vertical position at one side of said compartment, said second bed being movable with said pan from said horizontal position to said vertical position and pivotally mounted in the pan for movement relative thereto from the vertical position to horizontal operative position.

18. In a vehicle having a partition, a folding bed in the partition disposed vertically in inoperative position and movable to a horizontal operative position extending outwardly of the partition, means for mounting the bed in pivotal relation to the partition, means for counterbalancing the bed, a folding partition member mounted on the bed and foldable into the bed when the bed is inoperatively disposed and movable to a vertical operative position in spaced relation to said first-named partition when the bed is horizontal to provide a compartment in said vehicle individual to said bed, a second bed between said partitions extending within said first-named partition operatively disposed in parallel overlying relationship and in substantially vertical alignment with the first-named bed in its operative position, means pivotally supporting said second bed including a pan member hingedly mounted and movable from a horizontal position at a level higher than said vertically disposed first-named bed to a vertical position at one side of said compartment, said second bed being movable with said pan from said horizontal position to said vertical position and pivotally mounted in the pan for movement relative thereto from the vertical position to horizontal operative position, and means counterbalancing the weight of said pan and second bed during the operative movements.

19. In a vehicle having a space of substantially the length of a bed, a partition at one extremity of said space, a folding bed in the partition disposed vertically in inoperative position and movable to a horizontal operative position extending outwardly of the partition, and a second bed extending within said space operatively disposed in parallel overlying relationship and in substantially vertical alignment with the first-named bed in its operative position, said second bed being foldable in a direction at right angles to the folding movement of the first-named bed to an inoperative position out of the operative path of the first-named bed.

20. In a vehicle having a side wall, a ceiling and spaced dividing partitions disposed normal to the side wall, an intermediate drop partition depending from said ceiling between said dividing partitions, a pair of beds between said dividing partitions including a folding bed vertically disposed in inoperative position in each of the dividing partitions and movable to horizontal operative positions jointly extending between the partitions substantially in end abutting relation, a folding partition member mounted on at least one of said beds and foldable into the bed when the bed is inoperatively disposed and movable to a vertical position operatively associated with said drop partition when the bed is horizontal to separate the space between said dividing parti-

tions into individual compartments for the respective beds, a second pair of bed between said dividing partitions comprising an individually foldable bed operatively disposed in parallel overlying relationship and in substantially vertical alignment with each of the first-named beds in their operative positions, and means pivotally supporting each of said second beds including a pan member hingedly mounted and movable from a horizontal position at a level higher than said vertically disposed first-named beds to a vertical position adjacent said side wall, said second beds being movable with said pans from said horizontal positions to said vertical positions and pivotally mounted in the pans for movement relative thereto from the vertical positions to horizontal operative positions.

21. In a vehicle having oppositely disposed spaced dividing partitions, an intermediate drop partition between said dividing partitions, a pair of beds between said dividing partitions including a folding bed vertically disposed in inoperative position in each of the dividing partitions and movable to horizontal operative positions jointly extending between the partitions substantially in end abutting relation, a folding partition member mounted on at least one of said beds and foldable into the bed when the bed is inoperatively disposed and movable to a vertical position operatively associated with said drop partition when the bed is horizontal to separate the space between said dividing partitions into individual compartments for the respective beds, and a second pair of beds between said dividing partitions comprising an individually foldable bed operatively disposed in parallel overlying relationship and in substantially vertical alignment with each of the first-named beds in their operative positions, said second beds being movable in directions at right angles to the folding movements of the respective first-named beds to inoperative positions out of the operative paths of the first-named beds.

22. In a vehicle having oppositely disposed spaced dividing partitions, an intermediate drop partition between said dividing partitions, a pair of beds between said dividing partitions including a folding bed vertically disposed in inoperative position in each of the dividing partitions and movable to horizontal operative positions jointly extending between the partitions substantially in end abutting relation, and a folding partition member mounted on at least one of said beds and foldable into the bed when the bed is inoperatively disposed and movable to a vertical position operatively associated with said drop partition when the bed is horizontal to separate the space between said dividing partitions into individual compartments for the respective beds.

23. In a vehicle having oppositely disposed spaced partitions, a pair of beds between said partitions including a folding bed vertically disposed in inoperative position in each of the partitions and movable to horizontal operative positions jointly extending between the partitions substantially in end abutting relation, releasable means maintaining the respective beds in said horizontal operative positions, and means providing a separating wall between the beds at said abutting ends.

24. In a vehicle having a side wall and spaced dividing partitions disposed normal to the side wall, a pair of beds between said partitions including a folding bed vertically disposed in inoperative position in each of the partitions and

movable to horizontal operative positions jointly extending between the partitions substantially in end abutting relation, a folding partition member mounted on at least one of said beds and foldable into the bed when the bed is inoperatively disposed and movable to a vertical position when the bed is horizontal to separate the space between said dividing partitions into individual compartments for the respective beds, and an auxiliary member closing the space between said folding partition and said side wall.

25. In a vehicle having oppositely disposed spaced dividing partitions, an intermediate drop partition between said dividing partitions, a pair of beds between said dividing partitions including a folding bed vertically disposed in inoperative position in each of the dividing partitions and movable to horizontal operative positions jointly extending between the partitions substantially in end abutting relation, and a second bed extending between and pivotally supported from one of said dividing partitions and said drop partition disposed in parallel overlying relationship and substantially in vertical alignment with one of said first-named beds in its operative position and foldable in a direction at right angles to the folding movement of said first-named bed to an inoperative position out of the path of the first-named bed.

26. In a vehicle having oppositely disposed spaced partitions defining a pair of passenger accommodations convertible to day or night occupancy, a pair of seats for day use including a seat adjacent each of said partitions having a backrest foldable to a nighttime inoperative position, a pair of beds between said partitions for nighttime use including a folding bed vertically disposed in inoperative position in each of the partitions and movable when said backrests are folded to horizontal nighttime positions overlying said seats and jointly extending between the partitions substantially in end abutting relation, and means providing a separating wall between the beds at said abutting ends.

27. In a vehicle having a side wall and a partition disposed normal to the side wall defining one end of a passenger accommodation convertible to day or night occupancy, a seat for daytime use disposed adjacent to said partition and having a backrest foldable to a nighttime inoperative position, a folding bed in said partition disposed vertically in inoperative position and movable when said backrest is folded to a horizontal nighttime position overlying said seat, a partition defining the opposite end of said accommodation, and a second bed between said partitions disposed in parallel overlying relationship and in substantially vertical alignment with said first-named bed in its operative position and foldable in directions at right angles to the folding movement of the first-named bed to an inoperative position out of the operative path of the first-named bed.

28. In a vehicle having oppositely disposed spaced dividing partitions defining a pair of passenger accommodations convertible to day or night occupancy, a pair of seats for day use including a seat adjacent each of said dividing partitions having a backrest foldable to a nighttime inoperative position, a pair of juxtaposed individual seats intermediate said partitions and each disposed in opposite relation to one of the first-named seats, said last named seats being foldable to inoperative nighttime positions, a pair of beds between said dividing partitions for night-

time use including a folding bed vertically disposed in inoperative position in each of the dividing partitions and movable, when said backrests and intermediate seats are folded, to horizontal nighttime positions each overlying one of the first-named seats and one of the second-named seats and jointly extending between the partitions substantially in end abutting relation, a folding partition member mounted on at least one of said beds and foldable into the bed when the bed is inoperatively disposed and movable to a vertical position when the bed is horizontal to separate the space between said dividing partitions into individual compartments for the respective beds, and a second bed in each of said compartments disposed in parallel overlying relationship and in substantially vertical alignment with said first-named beds in their operative positions and foldable in directions at right angles to the folding movements of the first-named beds to inoperative positions out of the operative paths of the first-named beds.

29. In a vehicle having oppositely disposed spaced dividing partitions defining a pair of passenger accommodations convertible to day or night occupancy, a pair of seats for day use including a seat adjacent each of said dividing partitions having a backrest foldable to a nighttime inoperative position, a pair of juxtaposed individual seats intermediate said partitions and each disposed in opposite relation to one of the first-named seats, said last named seats being foldable to inoperative nighttime positions, a pair of beds between said dividing partitions for nighttime use including a folding bed vertically disposed in inoperative position in each of the dividing partitions and movable, when said backrests and intermediate seats are folded, to horizontal nighttime positions each overlying one of the first-named seats and one of the second-named seats and jointly extending between the partitions substantially in end abutting relation, and a second pair of beds between said dividing partitions comprising an individually foldable bed operatively disposed in parallel overlying relationship and in substantially vertical alignment with each of the first-named beds in their operative positions, said second beds being movable in directions at right angles to the folding movements of the respective first-named beds to inoperative positions out of the operative paths of the first-named beds.

30. In a vehicle having oppositely disposed spaced dividing partitions defining a pair of passenger accommodations convertible to day or night occupancy, a pair of seats for day use including a seat adjacent each of said dividing partitions having a backrest foldable to a nighttime inoperative position, a pair of juxtaposed individual seats intermediate said partitions and each disposed in opposite relation to one of the first-named seats, said last-named seats being foldable to inoperative nighttime positions, a pair of beds between said dividing partitions for nighttime use including a folding bed vertically disposed in inoperative position in each of the dividing partitions and movable, when said backrests and intermediate seats are folded, to horizontal nighttime positions each overlying one of the first-named seats and one of the second-named seats and jointly extending between the partitions substantially in end abutting relation, and means providing a separating wall between the beds at said abutting ends.

31. In a vehicle having a side wall and a parti-

tion disposed normal to the side wall defining one end of a passenger accommodation convertible to day or night occupancy, a second partition spaced from said first partition and disposed normal to the side wall defining one end of a passenger accommodation convertible to day or night occupancy, a seat for daytime use disposed adjacent to each of said partitions in oppositely facing relation and having backrests foldable to nighttime inoperative positions, a folding bed in each of said partitions disposed vertically in inoperative positions and movable when said backrests are folded to horizontal nighttime positions overlying said seats and extending in opposing relation, and means providing a separating wall between said beds at their opposing ends.

32. A full length bed vertically disposed in inoperative position and movable to a horizontal operative position, means for pivotally mounting the bed comprising a plurality of fulcrums about which the bed pivots including a first fulcrum comprising trunnion members disposed on respectively opposite sides of the bed cooperating with associated guide tracks, said tracks being fixed and stationary independent of the bed at respective sides thereof, a second fulcrum spaced vertically with respect to the first fulcrum and spaced outwardly with respect to the bed, a third fulcrum spaced vertically with respect to the second fulcrum and secured to the bed, strut means pivotally connecting said second and third fulcrums, said bed pivoting about said first fulcrum on an orbit traveled by said third fulcrum about the second fulcrum as defined by said strut means and guided by said guide tracks until the bed engages the second fulcrum whereupon the bed pivots directly thereabout to horizontal operative position, said second fulcrum being so located and disposed as directly to support the bed in operative position, and means for counterbalancing the bed throughout its operation.

33. A vehicle having a space of substantially the length of a bed, upper and lower beds in said space disposed in parallel overlying relationship substantially in vertical alignment when in operative position, said beds being foldable through intersecting planes in directions at right angles to inoperative positions, said upper bed being foldable about an axis extending longitudinally thereof and said lower bed being foldable about an axis extending laterally thereof.

34. A vehicle having a space of substantially the length of a bed, a lower bed in said space foldable from a horizontal operative position to a substantially vertical inoperative position at one end of the space, and an upper bed in said space disposed in operative position on a plane in parallel overlying relationship and substantially vertical alignment with the lower bed when the lower bed is in operative position and movable to an inoperative position disposed on a level above the inoperative position of the lower bed, said beds being foldable through intersecting planes in directions at right angles, said upper bed being foldable about an axis extending longitudinally thereof and said lower bed being foldable about an axis extending laterally thereof.

35. In a vehicle having a partition, a folding bed in the partition disposed vertically in inoperative position and movable to a horizontal operative position extending outwardly of the partition, and a second bed foldable in a direction at right angles to the folding movement of the first-named bed disposed in operative posi-

tion in substantially vertical alignment with the first-named bed in its operative position and movable to an inoperative position out of the operative path of the first-named bed, said beds being foldable through intersecting planes.

36. In a vehicle having a side wall and a partition disposed normal to the side wall defining one end of a passenger accommodation convertible to day or night occupancy, a seat for daytime use disposed adjacent to said partition and having a backrest foldable to a nighttime inoperative position, a folding bed in said partition disposed vertically in inoperative position and movable to a horizontal nighttime position overlying said seat, a partition defining the opposite end of said accommodation, and a second bed between said partitions disposed in parallel overlying relationship in substantially vertical alignment with said first-named bed in its operative position and movable to an inoperative position out of the operative path of the first-named bed, said beds being foldable through intersecting planes in directions at right angles.

37. In a vehicle having a side wall and a partition disposed normal to the side wall defining one end of a passenger accommodation convertible to day or night occupancy, a seat for daytime use disposed adjacent to said partition and having a portion movable to a nighttime position, a folding bed in said partition disposed vertically in inoperative position and movable to a horizontal nighttime position extending outwardly of the partition when said movable seat portion is moved to its nighttime position, a partition defining the opposite end of said accommodation, and a second bed between said partitions disposed in parallel overlying relationship and in substantially vertical alignment with said first-named bed in its operative position and movable to an inoperative position out of the operative path of the first-named bed, said beds being movable through intersecting planes in directions at right angles.

38. In a railway sleeping car, a section space of substantially the length of a bed, said space extending between a longitudinally extending aisle and a longitudinally extending car side wall, a transverse wall extending from said car side wall to said aisle and forming one end of said space, a ceiling and a floor at the top and bottom respectively of said space, a full-length foldable made-up bed extending, when in use position, lengthwise adjacent the floor along said car side wall and being foldable to a storage position extending vertically along said transverse wall, and another full-length movable made-up bed extending, when in horizontal use position, in vertically spaced parallel relation over the use position of said first-named bed and being movable in two stages of movement, including a first stage swinging movement, to a storage position adjacent the ceiling and outside the path of movement of said first-named bed.

39. A railway sleeping car having an occupancy space of substantially the length of a bed, said space extending between a longitudinally extending car side wall and a longitudinally extending aisle, a transverse wall extending from said car side wall and forming an end of said space, a floor and ceiling at the bottom and top respectively of said space, a full length foldable made-up bed extending, when in use position, lengthwise adjacent the floor along said car side wall and being foldable to a storage position extending vertically along said transverse wall, and another full-length movable made-up bed extend-

ing, when in horizontal use position, in vertically spaced parallel relation over the use position of said first-named bed and being movable in two stages of movement, including a first stage swinging movement, to a storage position adjacent the ceiling and outside of the path of movement of said first-named bed.

40. A railway sleeping car having an occupancy space of substantially the length of a bed, said space extending between a longitudinally extending car side wall and a longitudinally extending aisle, a transverse wall extending from said car side wall and forming one end of said space, a floor and ceiling at the bottom and top respectively of said space, a pair of made-up beds, one normally stored in vertical position against said transverse wall and in horizontal position adjacent the ceiling, respectively, of said space and the other being movable to use positions extending lengthwise and parallel to each other at lower and upper levels, respectively, along said side wall, for substantially the full length of the space.
